UNITED STATES PATENT OFFICE

168,729

CUP DISPENSER OR SIMILAR ARTICLE

Herbert L. Bennett, Easton, Pa., assignor to Dixie Cup Company, Easton, Pa., a corporation of Delaware

Application April 10, 1952, Serial No. 19,379

Term of patent 14 years

(Cl. D52—2)

To all whom it may concern:

Be it known that I, Herbert L. Bennett, a citizen of the United States and a resident of the city of Easton, in the county of Northampton and State of Pennsylvania, have invented a new, original, and ornamental Design for a Cup Dispenser or Similar Article, of which the following is a specification, reference being had to the accompanying drawing forming a part thereof.

On the drawing:

Figure 1 is a top plan view of the cup dispenser or similar article, showing my new design;

I claim:

The ornamental design for a cup dispenser or similar article, as shown.

HERBERT L. BENNETT.
